US0D1105012S

(12) **United States Design Patent** (10) **Patent No.:** **US D1,105,012 S**
(45) **Date of Patent:** **** Dec. 9, 2025**

(54) **REMOTE CONTROL**

(71) Applicant: **Remacro Technology Co., Ltd.**,
Jiangsu (CN)

(72) Inventor: **Wei Liu**, Jiangsu (CN)

(73) Assignee: **Remacro Technology Co., Ltd.**,
Suzhou (CN)

(**) Term: **15 Years**

(21) Appl. No.: **29/968,748**

(22) Filed: **Oct. 18, 2024**

(30) **Foreign Application Priority Data**

Aug. 14, 2024 (CN) 202430515637.9
(51) **LOC (15) Cl.** **14-03**
(52) **U.S. Cl.**

Primary Examiner — Selina Sikder

(57) **CLAIM**

The ornamental design for a remote control as shown and
described.

DESCRIPTION

FIG. 1 is a top, front and right side perspective view of a first
embodiment of a remote control showing my new design;
FIG. 2 is a bottom, rear and left side perspective view of
FIG. 1;

FIG. 3 is a front elevational view of FIG. 1;

FIG. 4 is a rear elevational view of FIG. 1;

FIG. 5 is a left side view of FIG. 1;

FIG. 6 is a right side view of FIG. 1;

FIG. 7 is a top plan view of FIG. 1;

FIG. 8 is a bottom plan view of FIG. 1;

FIG. 9 is a top, front and right side perspective view of a
second embodiment of the remote control;

FIG. 10 is a bottom, rear and left side perspective view of
FIG. 9;

FIG. 11 is a front elevational view of FIG. 9;

FIG. 12 is a rear elevational view of FIG. 9;

FIG. 13 is a left side view of FIG. 9;

FIG. 14 is a right side view of FIG. 9;

FIG. 15 is a top plan view of FIG. 9; and,

FIG. 16 is a bottom plan view of FIG. 9.

The broken lines in the drawings illustrate portions of the
remote control which form no part of the claimed design.

1 Claim, 16 Drawing Sheets
